UNITED STATES PATENT OFFICE.

CHARLES O. NORTHWOOD, OF WHITE MILLS, PENNSYLVANIA, ASSIGNOR TO C. DORFLINGER & SONS, INCORPORATED, OF WHITE MILLS, PENNSYLVANIA, A CORPORATION OF PENNSYLVANIA.

DESIGN FOR A GLASS GOBLET OR SIMILAR ARTICLE.

40,499.

Specification for Design.

Patented Feb. 8, 1910.

Application filed December 9, 1909. Serial No. 532,289. Term of patent 3½ years.

To all whom it may concern:

Be it known that I, CHARLES O. NORTHWOOD, a citizen of the United States, residing in White Mills, in the county of Wayne and State of Pennsylvania, have invented a new, original, and ornamental Design for a Glass Goblet or Similar Article, of which the following is a specification, reference being had to the accompanying drawing, forming part thereof.

The figure is a perspective view of a glass goblet or similar article showing my design.

I claim:

The ornamental design for a glass goblet or similar article as shown.

CHARLES O. NORTHWOOD.
